UNITED STATES PATENT OFFICE.

WILLIAM W. SLY, OF CLEVELAND, OHIO.

RUMBLE.

SPECIFICATION forming part of Letters Patent No. 769,192, dated September 6, 1904.

Application filed February 23, 1904. Serial No. 194,740. (No model.)

To all whom it may concern:

Be it known that I, WILLIAM W. SLY, a citizen of the United States, residing at Cleveland, in the county of Cuyahoga and State of Ohio, have invented new and useful Improvements in Rumbles, of which the following is a specification.

This invention relates to rumbles or tumbling-barrels, and particularly to such a device used for cleaning cast-iron pipes, and embodies the idea of enlarging the ends of the mill for the purpose of preventing wear incident to the flanges of the pipe.

In a simple cylindrical barrel or rumble the flanges of iron pipe tumbled therein contact edgewise with the walls of the barrel, with the result that in a short time the barrel is cut through and worn out. I remedy this defect by enlarging the ends of the barrel diametrically, so that the flanges of the pipe are contained in the enlarged diameters, which causes the pipe to lie flat in the barrel and obviates the wear above referred to.

In the accompanying drawings, wherein an embodiment of the invention is shown, Figure 1 is a plan view. Fig. 2 is an end view. Fig. 3 is a longitudinal section.

Referring specifically to the drawings, the body of the barrel is indicated at 6, and this may be constructed in any known or suitable manner, as of cast staves or of rolled plate metal. The enlarged ends are produced at both ends of this cylinder, conveniently by shrinking a ring 7 around the end of the cylinder and bolting thereto one end of a short cylinder 8, to the other end of which the head 9 is bolted. The body of the mill is provided with doors 10, secured by suitable fastenings, (indicated at 11.) Extending across each head, within the same, is a perforated plate 11^a of known construction, and the hollow trunnions 12 of the head lead to the dust-box 13, from which the dust may be exhausted in the

usual manner. Dust from the body of the mill or barrel escapes through the perforated plate and the trunnions to the dust-box. Gears for rotating the rumble are indicated at 14 and 15.

It will be appreciated that when pipe is put in the rumble to be cleaned the flanges at the end thereof will project into the enlargements produced at the end of the barrel, so that there will be no wear from the flanges and the pipe will lie flatly upon the wall of the barrel. In addition to avoiding the wear incident to the flanges this construction will clean pipe in a more efficient manner, since all of the outside of the pipe will or may be brought in contact with the wall of the rumble, so that all parts of the pipe, including the corners where the flanges join the tubular portion, will be cleaned.

Various modifications may be made in the shape, size, proportions, form, and construction of the rumble without departing from the scope of my invention, which is not limited except as indicated by the following claims.

What I claim as new, and desire to secure by Letters Patent, is—

1. A rumble comprising a cylindrical body, having a door therein, and an enlarged end constructed to receive enlarged ends of articles placed in the rumble.

2. A rumble comprising a cylinder, rings around the ends thereof, short cylinders of greater diameter secured to the rings, the interior of the cylinders being unobstructed, and heads fitted to the said short cylinders.

In testimony whereof I have signed my name to this specification in the presence of two subscribing witnesses.

WILLIAM W. SLY.
